HENRY KREISINGER, OF PIERMONT, NEW YORK, ASSIGNOR TO COMBUSTION ENGINEERING CORPORATION, OF NEW YORK, N. Y., A CORPORATION OF NEW YORK.

FURNACE-WALL PROTECTION.

Application filed August 23, 1923. Serial No. 658,904.

My invention relates to furnace wall protection, and is more especially concerned with furnaces adapted for burning fuel in suspension, such as pulverized or powdered coal, or even oil. I aim to obviate rapid deterioration or wasting away of the furnace walls through high temperatures and slagging; to prevent permanent fouling or encrustation of the walls with slaggy coating or other accretions of troublesome character; and to provide for prompt and easy removal of such refuse deposits on the walls as may occur.

For the sake of greater clearness, I have hereinafter explained my invention with special reference to the particular embodiment illustrated in the accompanying drawings, wherein is shown a furnace with powdered fuel burner directed downward into the combustion chamber adjacent one of the upright walls of the latter. It will be understood, however, that the invention is not limited to the particulars of the embodiment here illustrated, but can be otherwise carried out and applied.

In the drawings, Fig. 1 shows a vertical section through a steam boiler furnace for burning powdered coal, with provisions for the application of my invention therein.

Fig. 2 shows a vertical section through the combustion chamber at right angles to Fig. 1, taken as indicated by the line 2—2 in Fig. 1.

Fig. 3 is a fragmentary view of certain devices for removing deposits from the furnace walls.

Fig. 4 shows a cross section at right angles to Fig. 3, taken as indicated by the line 4—4 in Fig. 3.

As shown in Figs. 1 and 2, the furnace combustion chamber 10 is a large, deep, unobstructed chamber, enclosed by upright walls that slope outward slightly, so that the chamber as a whole expands upward. One or more powdered fuel burners 11 are directed downward into the combustion space or chamber 10 near its front wall 12, through the roof 13. As shown, such a burner 11 comprises an inner fuel pipe or nozzle with circumjacent air intakes. Powdered fuel with somewhat more than carrying air (preferably say, about 40% of the total air required for proper combustion) is fed in or admitted through the burner 11, and is continually ignited by the heat of the front

wall 12 and of the furnace generally. Air additional to that entering at the burner 11 is (or may be) supplied through inlet openings 14 at various heights in the front wall 12, so as to afford sufficient air to assure complete combustion, and even, if desired, to form a cooling zone in the bottom region 15 of the chamber 10. The burning stream (of mingled air, fuel, combustible gases from the fuel, and products of combustion) descends in the front of the chamber 10 until its momentum is overcome by the upward draft through the boiler. It then bends upward and ascends through the rear portion of the combustion chamber 10, finally passing upward therefrom to the boiler heating surfaces. (Here and elsewhere, I have used the terms "front" and "rear" in reference to the regions where the furnace is fired and whence the products of combustion make their exit from the main combustion chamber, respectively.) The size and depth of the chamber 10, the contiguity of the downward and upward fuel streams, and their change of direction as described assure rapid and complete combustion in the chamber 10; and high temperatures are developed.

The air admitted at the front wall inlets 14 may preferably be preheated. For this purpose, the combustion chamber walls may be built hollow, with a narrow space between the very highly refractory inner lining or curtain 20 and the outer shell 21, and the air may be passed through this intramural space on its way to the inlets 14,—thus also cooling the walls somewhat, and reducing the loss of heat by conduction through them. In the present instance, extra wide courses of the inner lining 20 serve as septa to divide the intramural space into damper-controlled and regulated horizontal ducts 22 at the levels of various inlets 14, as a means of controlling and regulating the distribution of this air over the lining 20 and to the inlets. Opposite the air supply openings 14 in the lining 20 are damper-controlled and regulated air intakes 23 in the outer shell 21, by means of which outside air can be admitted directly through the openings 14, in lieu of the heated air or in admixture therewith, either to supplement it or to regulate its temperature and assure adequate cooling in the zone 15. In the present instance, the rear wall 24 of the chamber 10

is shown solid, without interspace or ducts 22, but with a correspondingly thicker inner lining 20 of very highly refractory material.

The relatively heavy incombustible residue 5 from the fuel falls or precipitates toward the floor 25 and toward the walls 24 and 26 of the chamber 10, in a finely divided and molten condition. The refuse particles falling directly to the floor 25 encounter and 10 pass through the cooling zone in the lower region 15. This cooling zone 15 may be maintained either by an excess of air admitted as already described, or by a "water screen" consisting of a bank of water tubes 15 27 (sloping upward toward the rear) at a suitable height above the floor 25, or by both. In the cooling zone 15 (however it be maintained), the refuse particles are effectually cooled below fusion or slag-forming 20 temperature, so that they do not run together into a solid mass on the floor 25, but simply collect as dust that can be easily sucked out (or otherwise removed) at clean-out doors 28 at the rear. Or they may be 25 raked back and allowed to fall through a dump opening 29 in the floor 16 at the rear. The screen 27 also absorbs radiant heat from the subjacent deposit on the floor 25, and prevents refusion thereof by such heat from the 30 region of combustion above the screen.

The water tube boiler shown in Fig. 1 is of a familiar type, comprising a transverse drum 30 connected to vertical front and rear headers 31, 32 themselves interconnected by 35 banks of water tubes 33 inclined upward toward the rear. The water tubes 33 overlie an opening in the top or roof 13 of the chamber 10, and the furnace gases take a circuitous course amongst them (as defined by 40 the baffling shown, and indicated by the arrows) on their way to the furnace uptake and the stack. In the present instance, the ends of the screen tubes 27 are connected into front and rear headers 34 and 35, which 45 are themselves connected to the lower ends of the corresponding boiler headers 31 and 32 by downtime pipes 36 at the front and by uptake means including tubes 37, headers 38, and pipes 39 at the rear. Thus the 50 water screen is connected into the general boiler circulation in parallel with the water tubes 33, and acts to reinforce the circulation through the lowermost of the latter.

The temperatures obtaining in the combustion chamber 10 above the cooling zone 55 15 are so great that if no provisions were made to prevent, a wall or inner lining 20 of even the most refractory materials commercially available would be kept continually fused over its inner surface, and would "run" under the weight or drag of the molten refuse particles or slag continually passing from the flames to the walls and adhering. Also, it would be subject to scouring 60 and erosion by the refuse-laden gas cur-

rents. Hence the refractory furnace walls or lining would be speedily destroyed,—except, perhaps, at the front wall 12, which is cooled and protected somewhat by the air admitted through its inlets 14. The deterioration would tend to be especially severe at the rear wall 24, owing to the sweep of the flames toward and over the latter as they turn upward and ascend. 70

Or, again, if the cooling of the inner lining 75 20 by the intramural air circulation at 22 were sufficiently effective, the lining 20 might itself be kept from fusion, and instead acquire a coating of slag solid at the back, but fused and runny at its own exposed inner surface. Further accretions of the refuse would then run down to "freeze" 80 and build up in masses above the cooling zone 15. Such masses would remain and grow larger until forcibly broken away and 85 removed. This action, again, would be most pronounced at the rear wall 24.

Now I have discovered that such wastage and fouling difficulties of powdered fuel practice prior to my invention can be overcome by causing such refuse particles as 90 adhere to the upright walls to assume or deposit in a readily removable form,—for in some places and under some conditions, many, at least, of the particles striking the 95 walls may simply bounce off without adhering, and so fall to the floor 24. Under suitable conditions, initial deposit structures of 100 fragile mossy or "whiskery" character can be realized: in fact, formations so loose as to be quite friable and even pulverulent. Such character or formation can be given the refuse deposits by cooling effected substantially at the innermost wall surface,—as 105 contrasted with mere cooling effected between the general planes of the innermost and outermost surfaces of the wall. (Cf. the ducts 22 in Figs. 1 and 2.) In practice, a 110 most favorable condition seems to be the maintenance of a cool gaseous skin or lining on the internal surfaces of the walls. It is not generally necessary to admit or maintain over the wall a special layer of outside air: on the contrary, cooling of the thin outermost layer of the combustion chamber "atmosphere" answers the purpose quite well. 115

As here shown, the cooling is done by water tubes ranged along the innermost wall surfaces of the chamber 10. At the rear, the vertical tubes 37 that carry the upward circulation from the water screen 27 are arranged substantially against the wall 25 inside; at the sides, vertical tubes 41 are arranged substantially against the walls 26 on the inside. At their upper and lower ends, these side tubes 41 bend outward through the side walls 26 (like the upper ends of the rear tubes 37) and are connected to lower and upper headers 44, 45, which 120 125 may slope upward to the rear like the screen 130

tubes 27, to improve the flow through them. At the front, the lower ends of the lower headers 44 are connected to the boiler drum 30 by downtake pipes 46; while to the rear, 5 the upper ends of the upper headers 45 are connected by uptake pipes 47 and double-faced headers 48 into some of the horizontal return tubes 49 from the rear headers 32 to the front drum 30. Thus the side tubes 10 41 are connected into the general boiler circulation in parallel with the boiler tubes 33,—very much like the water screen tubes 27 and the rear tubes 37.

While considerable variation is admissible 15 or required under the various conditions of different installations, for that illustrated 3" to 4" tubes spaced 14" on centers represents fair practice for the tubes 27, 37, and 41.

20 By these tubes 37 and 41, therefore, a cool, thermo-protective gaseous lining of rather peculiar characteristics is maintained over the internal wall surfaces. First, this 25 gaseous lining causes adherent refuse particles to deposit on the rear wall 24 in easily removable forms, instead of in hard, adherent, runny-surfaced coating and mass formations of slag,—as already mentioned above. Secondly, this gaseous lining reduces the absorption of heat by the surfaces 30 of walls 24, 26 that it protects,—besides, incidentally, cooling them somewhat from the inside. (In other words, the tubes 37 and 41 cool the inner wall surfaces indirectly, 35 through the thermo-protective gaseous lining,—as contrasted with the direct cooling of the wall and merely incidental cooling of the gaseous layer thereon by the air in the intramural channels 22, for example.)

40 Thirdly, this cool, thermo-protective gaseous lining is necessarily quite thin, owing to the vigorous, free sweep of the flames through the interior of the chamber 10, and especially over the area of the rear wall 24. To 45 the extent of its limited thickness, this thermo-protective lining is not involved in the combustion, since it is at rather too low a temperature. However, it is so thin and so "stabilized" (so to speak) by the friction 50 and shelter of the walls 24, 26 and the tubes 37, 41, that its existence does not really affect the over-all efficiency of the furnace.

Where the cooling is especially thorough, 55 or the sweep of the flames less vigorous, an even more favorable action than just stated will result: i. e., the refuse particles will all be so much cooled as to bounce off from the combustion chamber walls without adhering at all, so that there will be no deposit.

60 This is notably the case over the side walls 26; in the corners of the combustion chamber; across the portion of the rear wall 24 behind where the flames are curving diagonally upward and rearward, and the cooling effects of screen 27 and rear tubes 37 over-

lap; and toward the top of the back wall 24, where the effects of rear tubes 24 and boiler tubes 33 overlap. (At the front wall 12, the influx of air through the openings 14 obviates any tendency for deposit to take 70 place).

Over the greater part of the rear wall 24, however, the phenomena are as above stated: loose, friable, pulverulent deposits are formed and grow in thickness rather rapidly. If this growth were allowed to go on unchecked, the highly thermo-insulative mossy structure would eventually attain a thickness between the tubes 37 such that the cooling effect of the latter would be more 80 or less lost. The deposit would then become harder and more cohesive, and would eventually begin to fuse and run at its inner surface,—just as in the case described above,—and runny masses of slag would 85 build up above the cooling zone 15. Owing to the inherent weakness of the mossy structure, masses of the slag-surfaced deposit would from time to time break loose and fall to the floor 25,—always, of course, with 90 the chance of lodging on the screen tubes 27 and interfering with the fall of refuse particles between them. In any case, the slagging at the inner surface of the deposit 95 would prove objectionable and troublesome.

To obviate such difficulties, I prefer to remove the deposit more or less continually or periodically, before it attains sufficient thickness to become runny at its exposed inner surface, or to assume any form more 100 troublesome or difficult of removal than its initial one. This makes it a very easy matter to keep the walls clean; because initially the deposits formed under the influence of the cooling at the inner surfaces of the furnace walls are so loose and even pulverulent in structure as to be detached or precipitated with the utmost ease,—either in fragile, friable fragments, or in a loose dust. It is 105 not generally necessary to resort to continuous percussion or vibration of the furnace wall: the loose formation may simply be periodically blown off the walls and thus dissipated,—very much as soot deposits are 110 blown off boiler tubes. In many installations 115 (as already intimated), this need not be resorted to regularly except for the rear wall 24.

In Figs. 1 to 4, a steam blower system 120 50 is shown for this purpose, comprising a lower header 51 with valved steam supply connection 52, individually valved vertical pipes 53 ranged across outside the rear wall 24 at intervals corresponding to the spacing 125 of the rear tubes 37, and rows of blower tubes 54 extending through the wall 24 midway between the tubes 57. As shown, there are three such tubes 54 to each pipe 53. At its inner end, each tube 54 is provided with 130 a flat blower head 55 that lies snug against

the wall 24, and has nozzle holes 56 arranged to discharge along the wall surface, obliquely toward and along the cooling tubes 37. The angle of discharge may vary considerably: e. g., $22\frac{1}{2}^{\circ}$ or 15° to the vertical, or even less.

The manner of burning the fuel has some bearing on the process described, for by virtue of the admission of only part of the air 10 with the fuel and the balance at successive points, a long, soft flame results which has a lower temperature than a short, clear, white flame and therefore there is less heat transmitted by radiation as between the 15 flame and any surface where there is deposit, and consequently the deposit of the refuse in the readily removable form described is facilitated. The use of water cooled tubes cuts down the air necessary in excess of the 20 theoretical, and thus decreases the volume of gases to be handled, and increases the efficiency and the amount of CO_2 in the stack gases.

What I claim is:

25 1. The method of obviating fouling of upright refractory furnace walls which consists in absorbing heat at spaced regions adjacent said wall by the indirect action of a cooling medium in order to cool the inter-

vening spaces sufficiently to cool the molten 30 refuse particles passing therethrough from the flame to the walls to such condition that they will adhere on lodging and assume a friable, mossy condition but will not form a solid mass, maintaining the deposit in such 35 condition by the action of said cooling medium and periodically dislodging it before the deposit has built out in the furnace to a point where it will run.

2. The method of obviating fouling of upright refractory furnace walls which consists in absorbing heat at spaced regions adjacent said wall by the indirect action of a cooling medium in order to cool the intervening spaces sufficiently to cool the molten 40 refuse particles passing therethrough from the flame to the walls to such condition that they will adhere on lodging and assume a friable, mossy condition but will not form a solid mass, maintaining the deposit in such 45 condition by the action of said cooling medium and periodically dislodging it by blowing it off before the deposit has built out in the furnace to a point where it will 50 run.

In testimony whereof, I have hereunto signed my name.

HENRY KREISINGER.
